UNITED STATES PATENT OFFICE

ADLOPHE GRIVIN, OF LONG ISLAND CITY, NEW YORK, ASSIGNOR TO SEA ISLAND MILLS, INC., OF NEW YORK, N. Y., A CORPORATION OF NEW YORK

DESIGN FOR A TEXTILE FABRIC OR SIMILAR ARTICLE

Application filed May 16, 1931. Serial No. 39,863. Term of patent 3½ years.

To all whom it may concern:

Be it known that ADLOPHE GRIVIN, a citizen of the United States, and resident of Long Island City, in the county of Queens and State of New York, has invented a new, original, and ornamental Design for Textile Fabric or Similar Article, of which the following is a specification, reference being had to the accompanying drawing, forming part thereof, in which the figure shows a fabric or similar article embodying my new design.

The portion of the drawing within the inner dot-dash line represents the unit which is repeated throughout the design.

I claim:

The ornamental design for textile fabric or similar article, substantially as shown and described.

Dated, May 12th 1931.

ADOLPHE GRIVIN.
